UNITED STATES PATENT OFFICE.

EHREGOTT T. WINKLER, OF KANSAS CITY, MISSOURI, ASSIGNOR OF ONE-THIRD TO
P. A. HILDEBRAN, ONE-THIRD TO D. P. GRAY, AND ONE-THIRD TO JOHN W.
ROBERTS, ALL OF KANSAS CITY, MISSOURI.

CONDENSER.

968,909.

Specification of Letters Patent. Patented Aug. 30, 1910.

Application filed February 8, 1909. Serial No. 476,710.

To all whom it may concern:

Be it known that I, EHREGOTT T. WINKLER, a citizen of the United States, residing at Kansas City, in the county of Jackson and State of Missouri, have invented certain new and useful Improvements in Condensers; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My present invention relates to condensers and more particularly to a device of that class for use in refrigerating systems.

It is the object of my invention to provide simple and effective means for cooling the 20 coils, within which a refrigerating agent is condensed, to the lowest practical degree, in order to maintain a low pressure against which the pumping mechanism of the refrigerating system may act.

25 It is a further object of my invention to provide a condenser in which a cooling liquid may circulate over the condenser in order to exercise economy in the cooling agent and to provide means for so controlling such cooling agent that the proper supply thereof for different condensing requirements may be automatically supplied.

It is a further object of my invention to 35 provide a condenser which may be so simple and economical in construction that it may be placed in refrigerating cars for the purpose of cooling such cars when in transit.

A further object of my invention is to provide the improved details of structure, 40 entirely described and pointed out in the claims, reference being had to the accompanying drawings, in which:—

Figure I is a central vertical section of a condenser constructed according to my invention. Fig. II is a similar view of a modified form of the condenser.

Referring more in detail to the parts:—1 designates the condenser base which also serves as the receiving pan for the 50 circulating liquid or cooling agent. At the center of the pan 1 is an upwardly directed drum 2 which forms an annulus in the pan 1 and an interior chamber which is utilized for dis-

tributing cooling air, as will presently be set forth. The drum 2 is preferably integral 55 with pan 1 and provided at its top with a sheet metal cylinder 3, having the perforations 4 therein, and provided with a cover 5 which entirely incloses the upper portion of the chamber inclosed by said drum and 60 cylinder.

Supported in the pan 1 is a casing 6 which is preferably set up from the pan bottom by the legs 7, in order that the cooling liquid may flow freely throughout the pan. Located 65 in the annulus, between the casing 6 and the drum and cylinder 2—3 are the brackets 8 upon which is supported a double coil 9—9', through which the refrigerating agent is adapted to flow, the coils opening from a 70 manifold 10 with which the pipe 11 from the refrigerating system communicates, and passing through separate apertures in the casing 6.

The coils are arranged at different distances from the central drum in order that a cooling agent may be distributed over both coils and be supported by the brackets. At 75 their lower ends the coils project through separate apertures in the casing 6 and empty 80 into a manifold 12 from which the pipe 13 leads back to the system in the top of the casing. Extending over the central drum and coils is a distributor for the cooling agent, which preferably comprises a hub 14 85 which is revoluble on the end of a supply pipe 15, and is perforated to provide exit ports for the cooling agent.

Pipe 15 leads to a pump 16 which takes water from the pan 1 and forces it upwardly into the distributor. The distributor 14 is revolved by the force of the water from the pump, but as this part is of a well known construction, I will not describe it in detail.

17 designates a supply pipe which empties into pan 1 and the flow through which is controlled by an automatic valve 18 having a float 19 for controlling the valve opening.

20 designates a blower which is located below the coils, preferably within the central drum, and preferably comprises fan blades and a motor for actuating same.

21 designates a hood on the casing 6 which is adapted for inclosing the condensing 105 parts.

When in use the refrigerating agent is delivered to the coils around the central drum and the pump operated to circulate a cooling agent over said coils, between the casing and central drum, the force of the water revolving the distributor when the structure illustrated in Fig. I is used, so that the cooling agent may be distributed equally over the coils. Simultaneously with the distribution of the cooling agent the blower is operated to discharge a blast of air over the cooling agent, preferably through the perforations in the central drum, so that the agent is cooled after its passage over a portion of the coils. When the cooling agent has passed over the coils it is caught in the pan 1 from which it is returned to the distributor through the medium of the pump and pipe 15.

With a condenser of this construction, the water, which is the usual cooling agent used, may be used until it is depleted by evaporation, when a fresh supply may be taken in from the pipe 17, the automatic valve controlling the level of the water in the pan, through the medium of the float 19.

In the modified form, the only changes made are by providing the inverted cone at the bottom of the central drum and forcing the air from the blower around the drum, at the bottom, instead of through the perforations, and the distributor which there consists of a perforated, plate covering for the casing. The operation of the modified form

is the same as that shown in Fig. I, as heretofore described. 35

Having thus described my invention, what I claim as new therein and desire to secure by Letters-Patent is:—

1. A condenser comprising a central drum, having perforations, a coil surrounding said drum, a casing inclosing said coil and drum, means for distributing a cooling agent over said coil, and means for forcing a blast of air into said drum and through said perforations. 40 45

2. A condenser comprising a central drum, having perforations in its sides and provided with a cover, a coil surrounding said drum, an outer casing inclosing said drum and coil, means for delivering a spray over said coil, and a fan located beneath the perforated portion of said drum and adapted for delivering air thereinto, for the purpose set forth. 50 55

3. A condenser comprising a central drum, a coil surrounding said drum, a casing inclosing said drum and coil, a fluid supply pipe terminating above the drum, a head revolvable on said pipe, and spray pipes carried by said head and adapted for travel over said coil. 60

In testimony whereof I affix my signature in presence of two witnesses.

EHREGOTT T. WINKLER.
